UNITED STATES PATENT OFFICE.

ALBERT H. SIMMONS, OF CHICAGO, ILLINOIS, ASSIGNOR TO UNION SPECIAL MACHINE COMPANY, OF CHICAGO, ILLINOIS, A CORPORATION OF ILLINOIS.

TRIMMING MECHANISM FOR SEWING-MACHINES.

1,253,737.

Specification of Letters Patent. Patented Jan. 15, 1918.

Application filed February 5, 1914. Serial No. 816,756.

To all whom it may concern:

Be it known that I, ALBERT H. SIMMONS, a citizen of the United States, residing at Chicago, in the county of Cook, State of Illinois, have invented certain new and useful Improvements in Trimming Mechanisms for Sewing-Machines, of which the following is a description, reference being had to the accompanying drawing, and to the figures of reference marked thereon.

The invention relates to new and useful improvements in trimming mechanisms for sewing machines, and more particularly to a trimming mechanism wherein the trimming members operate in substantially a horizontal plane in advance of a cross-stitching mechanism for trimming the edges of fabric, which edges are abutted and joined by cross-stitching.

An object of the invention is to provide a trimming mechanism wherein the movable trimming blade is positively reciprocated back and forth, and is held in proper contact with its coöperating member.

A further object of the invention is to provide a stationary trimming member which is so constructed that said member may be of considerable length without unduly projecting from the trimming point.

In the drawings, which show by way of illustration one embodiment of the invention,

Figure 1 is an enlarged perspective view, showing the presser foot, the trimming mechanism and the forward end of the work support;

Fig. 2 is a perspective view, showing the presser foot, the trimming members and clamping devices therefor, the parts being separated to show the structure; and

Fig. 3 is an enlarged sectional view through the presser foot at the needle slot.

The trimming mechanism embodying my improvement is of the type wherein the trimming blades operate in a horizontal plane in advance of cross-stitch mechanism, and relates particularly to the construction of the stationary knife and its supporting means, whereby a stationary trimming blade coöoperating with a movable blade may be made of considerable length without unduly projecting from the trimming point, and in which the curved stationary blade located in the recess of the presser foot may be adjusted as it is ground and sharpened so as

to maintain proper coöperative relation with the movable blade. This construction of the stationary blade not only permits a relatively long blade to be used, but also provides a very firm support for the blade as it is housed in the recess in the presser foot and the entire length of the blade is supported.

In the drawings, 1 represents the work support of a feed-up-the-arm machine, 2 the needle bar and 3 the needle, the needle bar as herein shown, being of the vibrating type, so that the needle zigzags back and forth across the line of feed making a cross stitch.

The presser foot bar is shown at 5, its supplemental bar at 6, and the presser foot shank at 7. Pivoted to a forked bracket 8 vertically adjustable on the extension 9 of the presser foot shank 7, is a rocking lever, one arm 10 of which is connected by a ball stud and clamp connection 11 with a pitman 12, which is operated in the usual way (not shown). The other arm 13 of the rocking lever carries the movable trimmer knife 14, held by the set screw 15. The adjustment 70 of the bracket 8 on the extension 9 through the set screw 16 and tongue and groove arrangement 17, enables the movable arm to be properly set with regard to the coöperating stationary blade, and the adjustable 75 plate 18 is set firmly against arm 13 when the knife is in position. The presser foot 19 is slotted at 20, and this slot extends from the forward end of the presser foot centrally thereof into the presser foot, and the side 80 walls of the slot are tapered outwardly.

The work support is provided with a V-shaped deflector 21, which turns up the edges of the fabric when sections are to be trimmed and joined, or forms a fold in the 85 fabric when a section is to be cut from the same and the edges afterward joined.

The needle 3 passes through a needle opening 22 formed in a cylindrical boss 23 carried by the presser foot 19. The slot 20 100 leads to the front face of the boss 23. The upper face of the presser foot is formed with an annular recess 24, the boss 23 forming the central wall of said recess. A stationary trimmer blade 25 is formed so as to fit said 105 annular recess 24.

In other words, this stationary trimmer blade 25 is annular in shape, having a central opening 26 which fits the boss 23. A section is removed from the blade, so as to 110

form a cutting edge 28. This stationary blade is placed in the recess 24 and is held therein by a clamping arm 29, which carries screws 30 adapted to press against the blade, as clearly shown in the drawings. This clamping arm is recessed as shown in Fig. 2 to allow proper clearance for the descent of the needle bar. A clamping screw 31 clamps the arm 29 to the presser foot, and causes the screws 30 to press against the blade to hold it firmly in the recess 24. When the blade 25 wears, it is removed and reground and shifted axially on the boss 23. The movable blade 14 is mounted so as to reciprocate in a substantially horizontal plane, and the presser foot is recessed as at 33 to form a guideway for this movable blade.

A bridge plate 34 spans the guideway 33 and is secured thereto by suitable screws. This bridge plate has a forwardly projecting arm 35, which supports the blade at a point adjacent the slot 20, that is, at a point adjacent the trimming line, and holds the blade in proper coöperative relation to the stationary trimming member 25.

In the operation of my device, the fabric is fed to the machine and the deflector 21 forms a fold in the fabric, so that as the fabric enters the slot in the presser foot, it will be in substantially vertical position. The trimmer blade trims off the portion of the fabric extending above the blade, after which the trimmed edges are abutted and are joined by cross threads. The trimmed-off strip is deflected to one side of the stitching mechanism by another deflecting device (not shown).

By increasing or decreasing the fold formed in the fabric, (that is, the amount of fabric which is cut from the piece,) tubular articles may be shaped and the trimmed edges joined. It will also be understood that two separate sections may be fed to the machine, and the deflector 21 will raise the edges so they will be substantially vertical and in position for action by the trimming mechanism.

It is obvious that minor changes in the details of construction may be made, without departing from the spirit of the invention as set forth in the appended claims.

Having thus described my invention, what I claim as new and desire to secure by Letters Patent, is:

1. A sewing machine including in combination, a presser foot having a slot in the forward end thereof leading into said presser foot, a needle, a trimming member movable across said slot in advance of the needle, a curved stationary trimming member carried by the presser foot and coöperating with said movable member, said stationary trimming member being shaped like a segment of an annulus of more than 180 degrees and

having one end thereof coöperating with said movable trimming member.

2. A sewing machine including in combination, a presser foot having a slot in the forward end thereof leading into said presser foot, a needle, a trimming member movable across said slot in advance of the needle, a curved stationary trimming member carried by the presser foot and coöperating with said movable member, said stationary trimming member being of substantially the same cross sectional area throughout and curved so as to substantially encircle the needle.

3. A sewing machine including in combination, a presser foot having a slot in the forward end thereof leading into said presser foot, a needle, a trimming member movable across said slot in advance of the needle, a curved stationary trimming member carried by the presser foot and coöperating with said movable member, said presser foot having a recess in its upper face, a central boss in said recess, and said stationary trimming member being curved to fit said recess.

4. A sewing machine including in combination, a presser foot having a slot in the forward end thereof leading into said presser foot, a needle, a trimming member movable across said slot in advance of the needle, a curved stationary trimming member carried by the presser foot and coöperating with said movable member, said presser foot having a recess in its upper face, a central boss in said recess, said stationary trimming member being curved to fit said recess, and said central boss having a needle opening therein through which the needle reciprocates.

5. A trimming mechanism comprising a movable blade and a fixed blade, said fixed blade being shaped like a segment of an annulus of more than 180 degrees and having one end thereof adapted to coöperate with the movable trimming blade.

6. A trimming mechanism for sewing machines including a movable trimming member, a support having an annular recess therein and a fixed trimming blade, said fixed blade being shaped like a segment of an annulus of more than 180° and having one end thereof adapted to coöperate with the movable trimming blade, and means for clamping said fixed blade in said recess.

7. A trimming mechanism including in combination, a presser foot, a movable trimming blade, means for moving said blade in substantially a horizontal plane, said presser foot having an annular recess in its upper face and a stationary blade coöperating with the movable blade, said stationary blade being shaped to fit said annular recess, and means for clamping said blade in said recess.

8. A trimming mechanism including in

- combination, a presser foot having an annular recess with a central boss formed with a needle opening therethrough, a movable trimming blade, means for moving said blade in substantially a horizontal plane, a stationary trimming blade coöperating with said movable blade, said stationary blade being shaped to fit said recess, and means for clamping said blade in said recess.
- 5 9. A trimming mechanism including in combination, a presser foot having an annular recess in its upper face forming a cen-
- tral boss provided with a needle opening, a trimming blade shaped to fit said recess, and means for holding the blade in said recess, 15 said presser foot having a slot in its forward end extending to said boss.
- In testimony whereof, I affix my signature in the presence of two witnesses.

ALBERT H. SIMMONS.
